UNITED STATES PATENT OFFICE

ARTHUR F. RIEDINGER, OF ST. LOUIS, MISSOURI

TOILET FIXTURE

Application filed November 23, 1929. Serial No. 409,316.

This invention relates broadly to toilet fixtures and has more particular reference to toilet fixtures which can be placed or set up in the wall of a building, which when in use may be swung outwardly to project from the wall and which when not in use may be swung inwardly within the interior of the wall to be completely hidden from view, and at the same time being so placed when not in use as to permit the utilization of the space the fixture would ordinarily occupy were it stationary, for other needed purposes.

A very important object of this invention is to provide a toilet fixture of the character above mentioned, the toilet fixture being preferably in the nature of a hopper.

In addition to the above, numerous other objects and advantages of the invention will readily present themselves during a study of the following description, taken in connection with the accompanying drawings, wherein:

Figure 1 is a fragmentary elevational view of a wall equipped with a toilet fixture as comprehended by the present invention, the toilet fixture being positioned within the wall and hidden from view.

Figure 2 is a similar view showing the toilet fixture in position for use.

Figure 3 is a vertical sectional view taken substantially on the line 3—3 of Figure 2.

Figure 4 is a transverse sectional view taken substantially on the line 4—4 of Figure 3.

Figure 5 is a similar view taken substantially on the line 5—5 of Figure 2.

Figure 6 is a fragmentary detail view partly in section and partly in elevation illustrating certain details of construction to be hereinafter more fully referred to.

Figure 7 is an elevational view of a supporting plate forming part of this invention.

With reference more in detail to the drawings, it will be seen that I have designated generally a conventional wall of a lavatory by the reference character W, and this wall may be of tile or any other suitable material.

As comprehended by the present invention, at a suitable height from the floor of the room the wall is provided with a suitable

opening or recess designated generally by the reference character 5. This recess, of course, opens at the front face of the wall. Secured to the wall around the outer edge of the opening is a suitable rectangular shaped frame designated generally by the reference character 6. The frame comprises shaped longitudinal upper and lower frame members 8, and vertical end frame members 8'. Upper and lower angular members 7 provide tracks for a sliding door 9, which door 9 may be made of any suitable material and is preferably so constructed as to resemble on its outer face the outer face of the wall W as shown to advantage in Figure 2. Obviously, the purpose of this door is for closing the opening 5. Extending upwardly through the wall and having its upper end arranged within the opening 5 is a waste pipe 10. The upper end of the waste pipe is suitably bracketed or supported within the opening through the medium of supporting brackets 11. A pipe fitting 12 has its lower end portion fitting telescopically within the upper end of the waste pipe 10, and intermediate its ends the coupling 12 is provided with an annular flange 13 adapted to seat within an enlarged socket 14 formed on the upper end of the waste pipe 10. The flange 13 cooperates with the bottom of the socket 14 to provide a ball race and said flange rests on ball bearings 15. The top face of the flange 13 is also provided to form a ball race in conjunction with an annulus 16 disposed about said coupling 12 and within which ball race are ball bearings 17. The annular member is held against rotation through the medium of set screws 18 threaded through the wall of the socket and disposed in sliding engagement with the adjacent peripheral edge of said annular member. This connection between the coupling 12 and pipe 10 also includes a suitable packing structure designated generally by the reference character 19. Thus it will be seen, that the coupling 12 is adapted for rotary movement in the upper end of the waste pipe 10. At its upper end, said coupling member is externally threaded for threaded engagement with one end of an elbow 20 as at 21.

Arranged in the recess 5 and adapted for horizontal swinging movement within said recess is a vertical partition or wall section 22. This wall section 22 on its outer face will resemble the outer face of the room wall W. This wall section 22 is adapted for horizontal swinging movement within the recess, and this wall section is of a height as to fit within the recess between the top and bottom of the recess, and said wall in width is such that when the wall section is swung for closing the open end of the recess said wall section will close substantially half of the opening of the recess so that said wall section may be disposed between one end edge of the opening and the sliding door 9 when the door is in that position shown to advantage in Figure 2 thus providing a complete closure for the recess when the wall section is in said position. The swingable wall section 22 is provided with a suitable opening 23, with which opening is aligned the other end of the elbow 20, said last mentioned end of the elbow 20 fitting within said opening in said movable wall as shown to advantage in Figure 3. Secured to the wall for moving therewith is a conventional hopper. Said hopper includes the usual bowl 24 secured to the movable wall section 22 in a manner to be hereinafter more fully set forth, the outlet of the bowl communicating with that end of the elbow 20 disposed within the hole or opening in said movable wall as also shown to advantage in Figure 3. The bowl is also suitably equipped with the hingedly mounted toilet seat 25.

Disposed rearwardly of the movable wall section 22 is a connecting plate 26 which plate 26 is preferably of that configuration shown in Figure 7, and this plate adjacent its upper end is provided with an opening 27 through which extends the last mentioned end portion of the elbow 20 and adjacent its lower end said plate 26 merges into a semi-circular clamp section 28 fitting about the upper end portion of the waste pipe 10. A complementary semi-circular clamp section 29 has outstanding apertured ears 30 at its opposite end disposed in registry with the apertured ears 31 of the clamp section 28 formed on the plate 26 and suitable connecting bolts 32 are passed through the apertured ears for clamping said sections 28 and 29 about said upper end of the waste pipe 10. Each of the clamp sections 28 and 29 are internally channeled or grooved and cooperate with a channeled annular flange 33 formed on said upper end of the waste pipe 10 to provide a ball race for ball bearings 34 as shown in Figure 3. Thus it will be observed that these clamp sections 28 and 29 in said clamped position are adapted for rotary movement about said pipe section 10. Said plate 26 adjacent its upper end is suitably formed to provide lateral ears 35 extending in parallel-

ism with laterally extending ears 36 projecting from opposite sides of the elbow 20, said ears 36 and 35 being suitably apertured for the reception of clamping bolts 37 as clearly suggested in Figure 3. Directly above the opening 27 adjacent its upper end the plate 26 is apertured as at 38, which aperture aligns with an apertured lug 39 rising from the top of the elbow 20 and a suitable bolt 40 has its opposite end threaded in the aperture 38 and the aperture of the lug 39 as is suggested in Figure 3.

The face plate 41 of the bowl fits against the outer face of the movable wall section 22, and this face plate is anchored to the wall through the medium of attaching bolts 42 which bolts 42 have one end thereof threaded in retaining nuts 43 embedded within the face plate 41. Said bolts 42 extending through suitable apertures in the movable wall section 22 and the lower end portion of the plate 26, and on the other ends of the bolts 42 are threaded nuts 44 for securing the pipe to the bowl. A suitable spacing nut 45 is threaded on the bolt 42 for disposition between the movable wall section 22 and plate 26.

The hopper structure is also equipped with the usual water inlet passage designated by the reference character 46, which passage 46 leads inwardly from the base plate 41 of the bowl, and at its entrance end there is arranged in the passage 46 and embedded therein a suitably flanged nut 47 which nut 47 is threaded on one end of the horizontal arm 48 of an L-pipe designated generally by the reference character 49, the upper end of the vertical arm 50 of said L-pipe having a swivel connection 51 with the water conduit pipe 52 leading from any suitable source of water supply. It is to be understood, that any kind of flushing apparatus may be used with this toilet fixture.

The arm 48 also extends through an aperture formed in the upper end of a vertical supporting rod 53 rising from the elbow 20 and also shown to advantage in Figure 3.

From the foregoing it will be seen that in using the fixture, the door 9 may be slid to the left in Figure 1 for movement within the wall structure W to an open position and then by grasping the bowl 24 the same may be swung in a horizontal plane thus swinging the wall section 22 to that position shown in Figure 2 for closing a portion of the opening leading into the recess 5 in the wall W, and the bowl will then be disposed in suitable position for use. The door 9 may then be drawn inwardly, or to the right of Figure 1 so that its forward edge may abut the adjacent vertical edge of the wall section 22 thus completely closing the opening leading to said recess 5 as is shown to advantage in Figure 2. When not in use, the door 9 may

be slid away from the wall section 22 and the bowl 24 and the wall section 22 then swung in a horizontal position for disposition completely within the recess 5, after which 5 the door 9 may be moved to right of Figure 1 completely closing the opening leading to the recess or to that position shown in Figure 1.

At its forward edge the door may be provided with a suitable socket 53 within which may be rotatably mounted a tissue supporting roller designated generally as at 54.

It is believed that from the foregoing description, taken in connection with the accompanying drawings, a clear understanding of the operation, construction, utility and advantages of a toilet fixture of this character will be had by those skilled in this art without a more detail description.

It is also apparent that in lieu of the toilet bowl suitable arrangements may be made whereby a wash bowl or like toilet fixture may be substituted therefor and swingably mounted within the recess 5 to be disposed therein when not in use or swung outwardly of the recess for disposition where ready use may be made thereof.

Even though I have herein shown and described the preferred form of my invention, 30 it is to be understood that the same is susceptible to certain changes fully comprehended by the spirit of the invention as herein described, and the scope of the appended claims.

Having thus described my invention what I wish to claim as new is:—

1. In a device of the character described, and in combination with a wall having a recess formed therein, upper and lower rails 40 mounted on said wall at the open end of said recess, a door slidably mounted between the rails for closing said recess, a waste pipe extending upwardly through said wall and having its upper end arranged in said recess, a pipe coupling rotatably supported in the upper end of said drain pipe, an elbow carried by the upper end of said pipe coupling, a vertically disposed wall section adapted for horizontal swinging movement within said 50 recess, said wall having an aperture therein adapted to receive the free end of said elbow, means for securing said wall section to said elbow, said wall section adapted to be swung to a position for partially closing the opening of said recess, a hopper mounted on said wall section, means for securing said hopper to said wall section whereby the outlet of said hopper will be in communication with said elbow, said hopper including a bowl and 60 a toilet seat hingedly mounted on said bowl, a flush pipe arranged within said recess and having one end in communication with the intake passage of said bowl, and means for 65 swivelly connecting the other end of said flush pipe to a suitable source of water sup-

ply, and said door adapted to be slid longitudinally between said rails in one direction for entirely closing the opening of said recess when said bowl is disposed within said recess, said door and said wall section cooperating with one another for entirely closing the opening of said recess when said wall section has been swung for disposition within the opening of said recess in vertical alignment with said first mentioned wall whereby said bowl may be positioned exteriorly of said recess to assume a position for use.

2. A support for toilet fixtures comprising in combination, a drain pipe, an elbow coupling rotatably mounted on the upper end of the drain pipe, a bowl supporting plate provided with an aperture for accommodating said elbow, a clamp carried by the plate and rotatably engaging said drain pipe, a toilet bowl, and means for securing said toilet bowl to said plate.

3. A support for a toilet bowl comprising in combination a relatively fixed member, a rotatable member on said fixed member, a plate adapted to be disposed substantially parallel to said fixed member, said plate provided with an aperture for accommodating the free end of said rotatable member, an integral clamp adjacent the lower end of said plate and rotatably engaging said fixed member, a bowl, and means for securing the same to said plate for rotation with said plate, and said rotatable member.

4. Means for swingably supporting a toilet fixture, comprising in combination, a drain pipe, an elbow swivelly mounted adjacent the upper end of said drain pipe, a supporting plate provided adjacent its upper end with an aperture for accommodating an end portion of said elbow, means for securing said plate to said elbow, and clamps carried by said plates for disposition circumjacent said drain pipe, and antifriction means interposed between said clamp and said drain pipe.

5. In combination, a drain pipe arranged in the recess of a wall, an elbow swivelly connected at one end to the upper end of said drain pipe, a bowl supporting plate, said plate provided with an aperture to accommodate the free end of said elbow, means carried by said plate adapted to rotatably engage in said drain pipe, a wall section closing said recess carried by said plate, and provided with an opening, the free end of said elbow being arranged in said opening, a toilet bowl having a waste outlet for registry with the free end of said elbow, and means securing said bowl to said wall section, said means including means for securing said wall section to said plate for rotation with said plate and elbow.

In testimony whereof I affix my signature.

ARTHUR F. RIEDINGER.
